Attorney.

UNITED STATES PATENT OFFICE.

ERNEST BERNIER, OF MONTREAL, QUEBEC, CANADA.

TICKET-HOLDER.

1,294,997.

Specification of Letters Patent.

Patented Feb. 18, 1919.

Application filed July 28, 1917, Serial No. 183,298. Renewed January 16, 1919. Serial No. 271,510.

To all whom it may concern:

Be it known that I, ERNEST BERNIER, a subject of the King of Great Britain, residing at 1236 Church St., Côte St. Paul, 5 in the city of Montreal, in the Province of Quebec, in the Dominion of Canada, have invented certain new and useful Improvements in Ticket-Holders; and I do hereby declare that the following is a full, clear, 10 and exact description of the same.

The present invention relates to improvements in ticket holders, and the object of the invention is to provide a simple, compact and cheap ticket holder that will hold 15 a plurality of tickets, and to provide means to deliver the tickets one at a time when wanted.

In order to more clearly disclose the construction, operation and use of the invention, reference will be made to the accompanying drawings forming part of the 20 present application.

Throughout the several figures of the drawings, like reference characters designate 25 the same parts.

In the drawings:

Figure 1 is a perspective view of the holder.

Fig. 2 is a sectional view through the 30 holder.

Fig. 3 is a perspective view of the delivery member.

Fig. 4 is a perspective view of the holder with one of its sides opened.

35 The holder comprises a casing 1 which is preferably provided with the hinged sides or covers 2 and 3 and horizontal slots 4 and 5 at one end adjacent to the top and bottom edges of said casing 1. The opposite 40 end of said casing is provided with an outwardly-bowed part 6, as disclosed in Fig. 4 of the drawings, and the adjacent edges of the covers 2 and 3 are similarly bowed or curved to fit thereagainst.

45 Within the casing are provided the movable plates 7 and 8, between which are located the coil springs 9 which press said plates 7 and 8 against the sides or covers 2 and 3; and between said plates and the 50 covers 2 and 3 are held a plurality of tickets 10.

The casing 1 is provided with the longitudinal slots 11 in the sides or covers 2 and 3; and in each of said slots is slidably mounted the shank 12 of the ejecting plate 55 13, and 14 is a button or head on the outer end of said shank 12.

Each plate 13 is movable within said casing 1 and is provided at one end with 60 a flange 15 which rests outside the adjacent plate 7 or 8 and is adapted to engage the edge of the uppermost ticket and push the same out through the delivery slots 4 or 5 when a longitudinal sliding movement is 65 impressed on said button 14. The flanges 15 on the plates 13 project into the space produced by the formation of the bowed portion 6 of the adjacent end member of the casing, which portion is expressly provided for that purpose, so as to insure the 70 normal disposition of the said flanges behind the ends of the presser plates 7 and 8, and, hence, extend substantially to the casing end in which the bowed portion 6 75 is formed, as shown in Fig. 2.

The tickets are inserted through the open sides 2 and 3, over which the said sides are closed.

It is thought that the construction, operation and use of the invention will be clear from the preceding detailed description.

What I claim as my invention is:—

In a ticket holder, the combination of a 85 casing provided with hinged covers at opposite sides thereof, each cover having a longitudinal slot; an ejector plate carried bodily by each cover and provided with a finger-piece which extends outward through 90 the slot therein, whereby said ejector plates may be slid forward and backward relatively to said covers and independently of each other; a pair of presser plates within said casing interposed between the ejector 95 plates, each presser plate and the adjacent ejector being adapted to contain between them a pack of tickets inserted upon the raising of the corresponding cover and the ejector plate carried thereby; and spring 100 means interposed between said presser plates for yieldingly forcing them away from each other in opposite directions and

toward the adjacent ejector plates, so as to press the packs of tickets against the latter; the front end member of the casing being formed with horizontal upper and lower delivery slots, and the rear end of each ejector plate being formed with a vertical flange which extends along the same and is normally disposed beyond the rear end of the adjacent presser plate in position

to engage the tickets and feed them one at 10 a time through the corresponding delivery slot when the ejector plate is advanced.

Signed at Montreal, Quebec, Canada, this third day of April, 1917.

ERNEST BERNIER.
